United States Patent

Des. 240,001
Patented May 25, 1976

240,001

SERVING TRAY

Austin F. Myers, 204 Sycamore Lane 17402, and William S. Ripley, 1171 Fairview Drive 17403, both of York, Pa.

Filed Sept. 18, 1973, Ser. No. 398,477

Term of patent 14 years

Int. Cl. D7—99

U.S. Cl. D7—27

FIG. 1

FIG. 2

FIG. 3

FIG. 1 is a top plan view of a serving tray showing our design.

FIG. 2 is a side elevation thereof.

FIG. 3 is a sectional view thereof taken on the line 3—3 of FIG. 1.

We claim:

The ornamental design for a serving tray, substantially as shown and described.
